CONRAD MUNKER, OF WASHINGTON, DISTRICT OF COLUMBIA.

AEROPLANE.

1,152,432.

Specification of Letters Patent. Patented Sept. 7, 1915.

Application filed December 13, 1909. Serial No. 532,856.

To all whom it may concern:

Be it known that I, CONRAD MUNKER, a citizen of the United States, residing at Washington, in the District of Columbia, 5 have invented certain new and useful Improvements in Aeroplanes, of which the following is a specification.

This invention relates to improvements in aeroplanes and particularly refers to 10 proved means for controlling and directing the flight of aeroplanes or heavier-than-air flying machines.

In the present state of the art it is the 15 practice of aviators to use vertically moving rudders, horizontal superposed shifting planes, flexible flight sustaining elements and warping mechanisms to vary the air pressures against such supporting planes in order to direct and control the flight of the 20 machines. The use of vertically moving rudders has not given uniform satisfaction, since such devices do not give the aviator adequate control of the moving planes and machines thus equipped are not as flexible 25 in their movements as is desired and necessary to the safety and efficiency of the machines. The control afforded by the warping or tilting of the planes is not wholly desirable, since such warping or tilting of 30 the planes tends to weaken the material of which the frame work of the machine is made and lessens the stability of the machine as a whole. This manipulation of the planes does not give the aviator that measure 35 of control that enables him to instantly vary the air pressures thereagainst in order to quickly and safely guide the machine over a circuitous course, or to correct any undesirable or dangerous lateral slants, such as 40 are produced by violent side gusts.

Broadly speaking, the present invention is designed to provide an improved aeroplane which will overcome the above and other objections to the adopted methods of 45 controlling the supporting planes.

One of the objects of the invention is the construction of an aeroplane having means for proportionately varying the air pressures against the supporting planes of the 50 machine, in the manner of a bird's wings.

Another object of the invention is the construction of an improved aeroplane having means for varying the air pressure against the supporting planes of the machine arranged so that the head resistance of the 55 machine will not be increased thereby.

A still further object of the invention is the construction of an improved aeroplane having supporting planes adapted to be operated in such a manner that the resistance 60 normally presented by said planes to the air can be proportionately varied at will, thus giving the aviator a control over the planes of the machine that will enable him to direct the same along a straight forward 65 path with the least resistance or round a curve with the greatest facility and safety, and thereby overcoming several of the inherent defects of present machines.

With the above and other objects in view, 70 the invention comprises certain combinations, constructions and arrangements of parts, clearly described in the following specification and clearly illustrated in the accompanying drawings, in which,

Figure 1 is a diagrammatic plan view, showing the machine as in full flight along a straight course; Fig. 2 is a similar view showing the machine rounding a curve; Fig. 3 is another plan view, showing the machine 80 in position for ascension or descension; Fig. 4 is a top plan view on an enlarged scale of one end of the machine, showing the lateral planes or wings thereof and the means for operating the same so that the air pressures 85 can be varied; Fig. 5 is a detail transverse sectional view, on an enlarged scale, taken on line 5-5 of Fig. 4; Fig. 6 is a detail transverse sectional view taken on line 6-6 of Fig. 5; Fig. 7 is a detail sectional view 90 of a set of pulleys used in operating the planes; and Fig. 8 is a detail view, showing the foot operated lever for controlling the pulleys and the planes. Fig. 9 is a fragmentary diagrammatic plan view, showing a 95 modification.

Referring to the accompanying drawings, which are illustrative of the invention and accordingly are not drawn to scale, 1 denotes the central frame, which may be of 100 any approved construction, and 2 and 3 the lateral plane or wing frames, each being shown in the drawings rigidly secured to the forward end of the central frame 1. It is obvious, that a single frame can be substituted for the two frames 2 and 3. The rear end of the central frame 1 is provided with the usual elevating planes 4 and with a steering rudder 5, which may be of any 105 desired construction. The elevating planes and the steering rudders are connected by suitable operating means, as rods, not

shown, to the central part of the machine so that the aviator can have adequate control over the same. A motor 6 is positioned on the forward end of the frame 1 for driving a suitable propeller 7.

5 The lateral plane or wing frames 2 and 3 are made alike. Each one of said frames comprises curved bars 8, disposed parallel to the side bars of the central frame 1, and bars 9 disposed transversely to said bars 8. The bars 8 are so arranged with respect to the bars 9 that each wing or lateral plane is made up of a plurality of divisions, rectangular in shape and adapted to receive the 10 flexible planes 10, which are movable within said divisions, four of which are shown for each wing frame.

15 The flexible planes are secured at their forward ends to spring rotated rollers 11, which are journaled between the bars 9 of the wing frames 2 and 3, while the other ends of said flexible planes are secured to operating ropes or chains 12, which extend through openings in the bars 9 to the operating pulleys. In order to guide the planes 10 between the bars 8 and to overcome a great part of the resistance which would result from a direct bearing of said planes on the bars, guide rods 13 are placed 20 between the fabric of the flexible planes or are secured thereto in any other manner, and the outwardly projecting ends of said guide rods are disposed in guideways 14, formed in the curved bars 8. The ends of 25 the rods 13 are preferably provided with friction rollers 15 adapted to allow free action of said rods, which construction also tends to prevent air from passing between the edges of the planes 10 and the bars 8.

30 35 40 The operating cords 12 are passed over guide pulleys 12* and are connected at their rear ends to multiple pulleys 16, which are mounted on shafts 17, secured in place to vertical frame members 18. On the outer 45 ends of the shafts 17, hand wheels 19 are mounted for the purpose of operating the pulleys. I contemplate the construction of mechanism whereby an even operation of the two sets of winding pulleys can be 50 effected simultaneously with the manipulation of one of these sets. Between the multiple pulleys 16 the seat 20 for the aviator may be positioned.

55 The pulleys 16 comprise a unit of three grooved wheels of different diameters. The cord connected to the outer flexible plane of each wing frame is connected to the largest of these wheels, 21; the cord connected to the next innermost flexible plane is connected to the next largest wheel 22; while the next plane is connected to the smallest wheel 23. The differences in the diameters of the wheels comprising the winding pulleys 16 may be great or small, as experience 60 dictates. As shown, the largest wheel 21 is

twice the diameter of the adjacent wheel 22, while the wheel 22 is twice the diameter of the wheel 23. Two planes 10* are rigidly secured, adjacent to the inner ends of the wing frames, thus insuring a constant supporting body for maintaining an even balance of the machine. 70

75 When the aviator desires to start the machine or to descend, the full spread or supporting area of the planes is desired. But when the machine has acquired a good speed, it is desirable that the resistance to the progress of the machine be diminished, or the area of the supporting planes be lessened, so that a greater speed can be 80 achieved with a given amount of power. In describing or rounding curves, the part or side of the machine nearest the center of the circle of which the curve is a part travels at a lower speed than the other side the 85 result being that said outer side of the machine tends to rise, thus unbalancing the machine. The shorter the curve and the greater the speed, the greater and more dangerous is the amount or degree of lateral 90 displacement of the machine as a whole. The air under the faster moving side of the machine is compressed to a greater degree than the air under the slower moving side of the machine. To vary this condition of the supporting air strata, it is the present custom to warp the supporting planes so that the air under the faster moving side of the machine will flow from said side with greater ease, and the tendency 95 of the machine to turn turtle will be 100 opposed. It is also the custom to effect this result by other methods which are applied in a manner similar to the warping method as previously pointed out. In the present 105 aeroplane, the difference in the air pressures against the faster moving and the slower moving side of the aeroplane is overcome by reducing the area of the supporting planes in such a manner that the air will 110 flow through the frame divisions in which the flexible planes work, thus permitting the escape of a portion of the volume of air 115 sustaining and lifting that side of the machine. The result of this arrangement being 120 that the machine will present, speed considered, an equal resistance to the air on both sides, when a curve is being described or rounded, and the machine will maintain its balance. When the machine is being moved 125 along a given straight course at a high rate of speed, the flexible planes may be operated so that the supporting plane area will be diminished in proportion to the speed of the machine. 130

135 From an examination of Figs. 1 and 2, it can be seen that the outer planes are opened to a greater degree than the inner planes and that the planes next to the outer planes are opened a lesser degree than the outer 140

planes and to a greater degree than the inner planes. This is accomplished by the pulleys 16. The peripheries of the larger wheels of said pulleys move or rotate at a greater speed than the peripheries of the smaller wheels thereof, so that said larger wheels will, in a given time, wind a greater amount of cord or chain. The flexible planes open forwardly by reason of the power of the spring rotated rollers 11, and are closed rearwardly by manual effort, exerted on the wheels attached to said pulleys.

Referring more particularly to Fig. 3, where the full area of the flight sustaining elements or supporting planes is shown, it will be observed that a comparatively large opposing surface is presented to any side gust. Should a side gust strike the planes, it will exert its greatest lifting power or leverage on the extreme outer planes, and to counteract this, I decrease the area of the planes in greater proportion toward the outside than toward the center of the machine, after the manner of a bird's wings, as illustrated in Fig. 1. In order to hold the flexible planes at a given position, I have provided a lever controlled ratchet mechanism. This mechanism comprises a ratchet wheel 24, which is suitably secured to each of the pulleys 16, a lever pawl 25, which is pivotally secured to a bracket 26, and is operatively connected to a depending foot rod 27, provided on its lower end with a foot engaged member 28. By applying foot pressure on the member 28, the lever pawl 25 is disengaged from the ratchet wheel 24 and the restraining action on the spring rollers 11 is thereby removed, so that said rollers will automatically open the flexible planes. When the planes have been opened to the extent desired, pressure on the member 28 is released, thus holding the planes in their adjusted positions. When it is desired to close the planes, power is applied to the wheels 19.

While I have shown and described the invention as adapted to monoplanes, it may equally as well be applied to biplanes and the like. It may be also said here, that although I have shown a plurality of flexible planes on both wing frames, and means to operate them simultaneously and at different speeds, it is obvious that I may employ a single flexible plane, on the outer end of each wing frame, and may employ means for operating these planes independently from each other. In some instances, I may find it desirable to make the rear edges of the individual supporting planes angular, so that such rear edges present a continuous diagonal edge from the center toward the outer side, irrespective of the area of the supporting planes as a whole, as shown in Fig. 9 of the drawings.

Having described my invention, I claim:

1. A sustaining plane, for an aeroplane, provided with openings, extending from near its center to near its ends; sets of movable elements arranged within the openings, and means to move the elements in each set at different speeds with relation to each other.

2. A sustaining plane, for an aeroplane, provided with openings, extending from near its center to near its ends; sets of movable elements arranged within the openings, and common means connected with the elements in each set and adapted to move the outer element at a greater rate of speed than the adjacent inner element.

3. A sustaining plane for an aeroplane, adapted to be arranged transversely to the line of flight; and means to longitudinally taper the plane so that it decreases in width toward its ends.

4. An aeroplane including supporting planes composed of independent folding sections, and operating means connected to the independent sections for folding the same proportionately to their distances from the central portion of the aeroplane.

5. An aeroplane including a central frame, a plurality of flexible supporting planes arranged on each side of the central frame in parallelism to each other and to the line of flight of the machine, and operating means connected independently to the flexible planes for diminishing the same to reduce the air opposing areas thereof for regulation of the different speeds of the machine.

6. An aeroplane including a central longitudinal frame, lateral planes projecting from said central frame and having spaced cross bars, spring operated rollers journaled between the forward ends of said cross bars, flexible planes carried about the rollers and extending between said cross bars, operating cords carried by the lateral frames and connected to the free ends of the flexible planes, and pluralities of pulleys varying in diameter carried by said central frame and receiving the opposite ends of said cords.

7. An aeroplane provided with a plurality of planes movable parallel to the line of flight of the machine and means for moving the outer planes at a greater speed than the adjacent planes.

8. A sustaining plane for an aeroplane, adapted to be arranged transversely to the line of flight, and means to longitudinally taper the rear longitudinal edge of the plane so that it decreases in width toward its ends.

9. An aeroplane having frames, a plurality of folding planes carried upon the frames and adapted to be normally closed, and operating means connected to all of said planes for opening the same at rates of speed increasing proportionately to their distances from the center of the frame, the planes of

- one frame being operated independently of the planes of the other frame.
10. An aeroplane provided with a plurality of inner and outer planes, and means for moving the planes with relation to each other, and the outer planes at a greater rate of speed than the inner planes.
11. An aeroplane having a rigid central frame, wing frames rigidly connected thereto, bars forming guides on the wing frames, spring rollers journaled between the bars, flexible planes connected to the rollers movable between the bars, guide rods secured to the planes adapted to ride in the bars, winding ropes connected to the planes, and multiple pulleys having wheels of different diameters connected to the ropes.
12. An aeroplane having a central frame, wing frames connected thereto, bars on the wing frames having guideways, spring rollers journaled to the wing frames, flexible planes connected to the rollers and movable between the bars, guide rods on the planes having rollers on their ends movable in the guideways of said bars, ropes connected to the planes, multiple pulleys connected to the ropes having wheels of different diameters adapted to wind the ropes at different speeds, and means for holding the planes in fixed position.
13. An aeroplane provided with a central frame, wing frames secured to the forward end of said central frame, guide bars on the wing frames disposed in lines parallel to the central frame, flexible planes between the guide bars, guide rods on the flexible planes adapted to bear on the guide bars, spring rotated rollers journaled between the guide bars for rolling the flexible planes to diminish their area, operating cords connected with the flexible planes, multiple pulleys comprising wheels of different diameters connected with the cords for differently diminishing the area of the flexible planes, a ratchet wheel on the multiple pulleys, lever pawls pivoted to engage the ratchet wheels, and depending foot operated rods for disengaging the lever pawls from the ratchet wheels.
14. An aeroplane provided with a central frame, wing frames secured to the forward end thereof, guide bars on the wing frames dividing said frames into rectangular divisions having lengths parallel to the central frame, flexible planes rollable at different speeds between the guide bars, and means carried by the planes adapted to guide the movements of the planes between the guide bars and prevent air from passing through the edges of the planes and the bars.
15. In an aeroplane, a central frame, sustaining planes connected with the frame and extending upon opposite sides thereof, transversely to the line of flight; and means whereby the sustaining planes may be longitudinally tapered independently of each other, substantially as described.
16. An aeroplane having a central frame, horizontal lateral frames carried by the central frame and being curved transversely downward at their rear ends to approach a vertical plane, a plurality of longitudinally foldable flexible planes arranged in the lateral frames, and operating means connected to the flexible planes for moving the same proportionately to their distances from the central frame.
17. An aeroplane including a central frame, laterally extending frames carried by the central frame and having transverse sections therein, flexible planes movable in the transverse sections of said lateral frames, and means carried by said central frame for moving the flexible planes fore and aft to vary the effective areas thereof.

In testimony whereof I affix my signature in presence of two witnesses.

CONRAD MUNKER.
